Filed Jan. 16, 1958, Ser. No. 709,368

24 Claims. (Cl. 315—3.5)

This invention relates to traveling wave electron discharge devices and more particularly to broadband radio frequency impedance matching devices to provide a substantially reflectionless impedance transformation between relatively high impedance propagating structures, such as a helical propagating structure, and relatively low impedance input and output radio frequency transmission lines usually employed in such discharge devices.

One of the problems in the helix type of traveling wave tube is in obtaining a broadband impedance match between radio frequency transmission lines and the helical wave propagating structure. A helix type of traveling wave tube may have a useful operating frequency range of over 2 to 1, with the useful range limited by the quality of the radio frequency impedance match. It is known that to cover a 2 to 1 or greater operating frequency range, coaxial line radio frequency circuit connections are usually resorted to since waveguide transmission lines have well known bandwidth limitations. The characteristic impedance of coaxial lines may be in the order of 50 ohms, while the circuit impedance of traveling wave tube helices may be in the order of several hundred ohms. There is then, clearly, the problem of matching a low impedance coaxial radio frequency line to a helical radio frequency line of a much higher impedance than the coaxial line.

There are a number of different types of impedance matching arrangements which have been employed in the past to accomplish the impedance matching between a coaxial transmission line and a helical transmission line. In certain applications a cylindrical ground sleeve may be disposed in close spaced relation to that of the helix such that the impedance between the helix and the ground sleeve is in the order of the impedance of the coaxial transmission line, thereby enabling a direct connection between the helix and the coaxial transmission line. In other applications, this helix-above-ground plane impedance transformation cannot be carried to the extent that the impedance between the helix and the ground plane is reduced to that of the impedance of the coaxial transmission line. This necessitates the necessity of incorporating a tapered transformer arrangement in the coaxial transmission line. At the lower frequencies, there often is not room enough for this type of transformer in the coaxial line. Therefore, other arrangements have to be resorted to.

An object of this invention is the provision of means to provide a useful operating frequency range for a helix type of traveling wave tube of over 2 to 1.

Another object of this invention is to provide an improved means for matching a low impedance radio frequency line to a high impedance wave energy propagating line of helical configuration.

A feature of this invention is the provision of a broadband radio frequency impedance matching device for use between a relatively low impedance wave energy propagating line and a relatively high impedance wave energy propagating line comprising a spiral conductor and a

2

ground conductor disposed in tapered spaced relationship.

Another feature of this invention is the provision of a broadband radio frequency impedance matching device for use between a relatively low impedance wave energy propagating line and a relatively high impedance wave energy propagating line comprising in combination first and second impedance transition sections and means coupling equal impedance points of said first and second transition sections to each other. The first transition section is characterized by including a conducting cylinder and a helical conductor disposed within and coaxially of said cylinder, the spacing between said conducting cylinder and said helical conductor being tapered from a narrow spacing to a relatively wide spacing and said second transition section is characterized by including a spiral conductor and a conductive surface disposed in tapered spaced relation.

Still another feature of this invention is the configuration of the second transition section of the impedance matching arrangement of this invention which includes a conductive disk disposed coaxially of and extending radially from a given axis and a conductive spiral disposed coaxially of said given axis and in tapered spaced relationship with respect to one of the planar surfaces of said disk.

A further feature of this invention is the provision of the second transition section of the impedance matching arrangement of this invention having the configuration including a conductive cylinder and a conductive spiral disposed within and coaxially of and extending along the longitudinal axis of said conductive cylinder in tapered spaced relationship with the inner surface of said conductive cylinder.

Still a further feature of this invention is the provision of the second section of the impedance matching device of this invention wherein the input second transition section is a spiral conductor disposed in tapered spaced relationship with one planar or ground surface of a disk extending radially from and coaxial of the axis of the propagating structure of a traveling wave tube, and the output second transition section is a spiral conductor disposed in tapered spaced relationship with the other planar or ground surface of the same disk, and means are provided to couple the second transition section to the first transition section of the input and output impedance matching devices.

The above mentioned and other features and objects of this invention will become more apparent by reference to the following description taken in conjunction with the accompanying drawings, in which:

Fig. 1 is a cross-sectional view of a traveling wave tube illustrating an impedance matching device following the principles of this invention;

Fig. 2 is a cross-sectional view taken along line 2—2 of Fig. 1;

Fig. 3 is a cross-sectional view of an alternative arrangement of the impedance matching device illustrated in Fig. 1;

Fig. 4 is a cross-sectional view of another embodiment of the impedance matching device following the principles of this invention;

Fig. 5 is a cross-sectional view of a traveling wave electron discharge device illustrating still another form that the impedance matching device of this invention may take; and

Fig. 6 is a cross-sectional view of a traveling wave electron discharge device incorporating still another form of impedance matching device following the principles of this invention.

Referring to Fig. 1, a traveling wave tube is illustrated in conjunction with one form of impedance matching device following the principles of this invention. The

traveling wave tube is illustrated as including an envelope 1 including therein an electron gun 2 to project an electron beam along a given path to collector electrode 3. Disposed in interacting relation with the electrons of the electron beam is a propagating structure 4 wherein amplification of wave energy takes place through the interaction with the electrons of the electron beam. As is well known, the wave energy to be amplified may be coupled to the input of the traveling wave tube by a coaxial transmission line 5, and the amplified wave energy may be coupled from the output of the propagating structure 4 by means of coaxial transmission line 6. To assure a broadband reflectionless amplification of the wave energy in the traveling wave tube, it is necessary to match the relatively low impedance of the input and output lines 5 and 6 to the relatively high impedance at the input and output ends 7 and 8, respectively, of helical propagating structure 4.

In accordance with this invention, the impedance match to provide this reflectionless coupling of energy at the input end of propagating structure 4 is accomplished by employing a first transition section 9 and a second transition section 10. The first transition 9 includes a conducting cylinder 11 coaxial of the axis of the helical propagating structure 4 and a helical conductor 12 disposed coextensive with and within and coaxial of cylinder 11. As will be noted, helical conductor 12 is coupled to the input end of propagating structure 4 and is aligned along the axis thereof. It will be further noted that cylinder 11 is characterized by three portions, portion 13 providing a relatively wide spacing between cylinder 11 and helical conductor 12, portion 14 providing a relatively narrow spacing between cylinder 11 and helical conductor 12 and a tapered portion 15 which gradually varies the spacing between cylinder 11 and the conducting helix 12 between portions 13 and 14. With this arrangement the impedance of the first transition section 9 in the vicinity of portion 13 of cylinder 11 is substantially equal to the characteristic impedance of propagating structure 4. The tapered section 15 gradually reduces this impedance to a value intermediate the relatively high impedance of propagating structure 4 and the relatively low impedance of the coaxial transmission line 5.

An extension of helical conductor 12 provides an electrical connection between transition section 9 and transition section 10 as shown at 16. It is to be understood that, while Fig. 1 illustrates the coupling between the two transition sections, to be an extension of helical conductor 12, this connection may be provided by a coaxial transmission line having a characteristic impedance substantially equal to the impedance of the first transition section in the portion 14. The second transition section 10 includes a disk 17 disposed coaxially of the longitudinal axis of propagating structure 4 and extending radially therefrom. As illustrated, disk 17 may be a portion of the magnetic pole piece energized by magnetic means 18 to aid in maintaining the electron beam at a substantially constant diameter as it passed through propagating structure 4. It is to be remembered, however, that disk 17 may be any disk disposed in the manner illustrated in Fig. 1 to behave as a ground conductor. In spaced tapered relationship with respect to a planar surface of disk 17 is disposed a spiral conductor 19, such that the spiral conductor 19 is in tapered spaced relation with the planar surface 20 of disk 17 such that the widest spacing between surface 20 and spiral 19 is adjacent the longitudinal axis of propagating structure 4, and the narrowest spacing between spiral 19 and surface 20 is disposed along disk 17 removed from the longitudinal axis of propagating structure 4. It will be noted that spiral 19 is wound to occupy two planes intersecting at the axis of propagating structure 4 with these two planes being in a tapered relation with the

planar ground conductor 20 as illustrated. The spiral configuration and relationship to the axis of the propagating structure 4 is shown in more detail in Fig. 2. Coupling means 16 is connected to spiral 19 in the region where spiral 19 is spaced the widest from planar surface 20 with the height of the spiral conductor 19 above surface 20 being such as to provide an impedance substantially equal to the impedance present in region 14 of the first transition section 9. The low impedance propagating structure 5 is coupled at spiral conductor 19 in the region where spiral conductor 19 is spaced the least amount from planar surface 20 and where the height of spiral 19 above surface 20 provides an impedance substantially equal to the characteristic impedance of the coaxial transmission line 5. Thus, through this arrangement, wave energy is coupled from coaxial transmission line 5 to propagating structure 4 in a reflectionless manner since the impedance of these two propagating structures are matched through cooperation to the two transition sections 9 and 10.

The impedance match at the output end of propagating structure 4 between the characteristic impedance of propagating structure 4 and the output coaxial line 6 is accomplished in substantially the same manner as illustrated at the input end of propagating structure 4, and the structure thereof will not be discussed in detail herein, but reference may be had to the discussion of the input impedance matching device, like components thereof being identified by the same reference characters as employed for the impedance matching device but primed.

As illustrated in Fig. 1, the spacing between spiral 19 and planar surface 20 is accomplished by employing a dielectric material 21 having the appropriate tapered configuration to provide the desired height of spiral 19 above surface 20 along the radial dimension thereof. An appropriate material for this dielectric spacing is Teflon.

As illustrated in Fig. 1, the spiral 19 was spaced from the planar surface 20 facing toward the middle of the traveling wave tube. It is to be understood that spiral 19 may be spaced in tapered relationship from the other surface of disk 17 such that the spiral faces toward an end of the traveling wave tube. Such a configuration is illustrated in Fig. 3 wherein spiral 19 is spaced in a tapered relationship from planar surface 22 of disk 17. In this arrangement, it would be possible to dispose the magnetic means 18 closer to the axis of the propagating structure 4 and, hence, the size of the magnetic means 18 could be reduced since the magnetic field is now closer to the axis wherein its effect must be felt. The remainder of the impedance matching device is substantially identical with that illustrated in Fig. 1, and the components are identified by identical reference characters.

Employing the arrangement illustrated in Fig. 3, it is preferable to shield spiral 19 by means of an arrangement such as illustrated at 23 to prevent undesired radiation therefrom. This shielding arrangement 23 was not necessary in the configuration illustrated in Fig. 1 since the magnetic means 18 and cylinder 11, in effect, provide the desired shielding arrangement.

Referring to Fig. 4, there is illustrated another form which the impedance matching device of this invention may take. The first transition section 9 of the impedance matching device is substantially identical as that illustrated in Fig. 1, and reference characters as employed in Fig. 1 are shown in Fig. 4. The second transition section of the impedance matching device in accordance with this embodiment still employs a spiral in tapered relationship with a ground surface but is structurally obtained in a different manner. In accordance with the embodiment illustrated in Fig. 4, the second transition section 10 is composed of a conducting cylinder 24 and a spiral conductor 25 disposed coaxially of and extending along the longitudinal axis of cylinder 24 such that a tapered rela-

tionship exists between the inner surface 26 and the spiral conductor 25 substantially as illustrated. In this arrangement, the dielectric material between surface 26 and conductor 25 is air. As before, in connection with Fig. 1, the coupling means 16 is coupled to spiral conductor 25 and surface 26 in the region of transition section 10 where the widest spacing occurs between spiral 25 and the ground surface 26, while the low impedance transmission line 6 is coupled to spiral 25 and surface 26 in the region of the narrowest spacing between spiral 25 and ground surface 26. As in the configuration of Fig. 1, the points of coupling between the two transition sections is chosen so that the impedance of transition section 9 in the region 14 thereof equals the impedance of a transition section 10 at the point where coupling means 16 is connected thereto. Spiral 25 is mounted on a dielectric frusto conical member 27 which, in turn, may be mounted on a radially disposed disk member 28 which also serves to support cylinder 24 and, in effect, may be considered as part of the ground surface. Disk 28 may be a portion of the magnetic circuit as discussed in connection with Fig. 1 or may be a separate radially extending component of the traveling wave tube or a separately applied component to carry out the impedance matching of this invention.

In the arrangement of Fig. 1, it is contemplated that the input transmission line 5 will be brought in at one end of the traveling wave tube for connection to the input end 7 of the propagating structure 4, and the output transmission line 6 will be brought in at the other end of the traveling wave tube for connection to the output end 8 of the propagating structure 4. As is well known, there are certain advantages to having the input and output transmission lines brought in to the traveling wave tube at one end thereof. Such an arrangement is illustrated in Fig. 5 wherein input line 29 is brought in adjacent the output end of propagating structure 4, and the output line 30, as is the usual practice, is taken out at the output end of the propagating structure 4. The impedance match for this arrangement may be carried out as described herebefore in accordance with the principles of this invention and with certain modifications thereto hereinafter described. As described in connection with Fig. 1, the impedance matching device is composed of two transition sections. The first transition section is identical to that illustrated in Fig. 1 with the first transition section of the input impedance matching device being identified as 9 and the first transition section of the output impedance device being identified as 9'. The portions of these first transition sections are identical to that illustrated in Fig. 1 and the corresponding reference characters are applied thereto in Fig. 5.

The second section of the input and output impedance matching devices are illustrated as being disposed at the output end of the propagating structure 4. The second section of the input impedance matching device is illustrated as including a spiral conductor 31, substantially identical in configuration and purpose as spiral 19 in Fig. 1, spaced in tapered relationship with the planar surface 32 of disk 33. Both disk 33 and spiral 31 are disposed coaxially of the longitudinal axis of propagating structure 4 and extend radially therefrom. As in the embodiment of Fig. 1, the input coaxial line 29 has its outer conductor coupled to disk 33, and its inner conductor coupled to spiral 31 such that the impedance between spiral 31 and planar surface 32 equals the characteristic impedance of coaxial line 29. The impedance of this spaced spiral 31 and planar surface 32 increases to a value intermediate the low impedance of the coaxial line 29 and the high impedance of propagating structure 4 at a point adjacent the longitudinal axis of propagating structure 4. At this point, the coupling means 16 is coupled to the second transition section which, in this instance, is constituted by coaxial transmission line 34 which extends from the second transition section 10 to the first transi-

tion section 9 of the input impedance matching device, thereby connecting equal impedance points of transition sections 9 and 10.

The second section 10' of the output impedance matching device is disposed in spaced tapered relationship with planar surface 35 of disk 33 such that the impedance of output coaxial line 30 is matched to that of the characteristic impedance of propagating structure 4 in substantially the same manner as described in connection with section 10 of Fig. 5 of section 10 of Fig. 1. The coupling between the first and second transition sections 9' and 10', respectively, is accomplished by means of extension of helical conductor 12' as indicated at 16'.

Referring now to Fig. 6, there is disclosed therein an arrangement whereby the second transition section disclosed in Fig. 4 may be utilized in conjunction with a traveling wave tube wherein the input and output transmission lines are coupled to the traveling wave tube from the same end thereof. The first transition section of the impedance matching device is substantially identical to that described in connection with Fig. 1 and like reference characters for the first transition section will be employed herein. The second transition section 10 for the input impedance matching device in this instance is composed of a cylinder 36 and a spiral conductor 37 disposed coaxially of and extending along the longitudinal axis of cylinder 36 in tapered spaced relationship with the inner surface 38 of cylinder 36. It will be observed that the longitudinal axis of cylinder 36 is disposed at right angles to the longitudinal axis of propagating structure 4 to conserve on axial length. As described in connection with Fig. 4, the input transmission line 39 is coupled to spiral 37 at a point where the impedance of the second transition section 10 substantially equals the characteristic impedance of coaxial line 39 which occurs in the region of the narrowest spacing between spiral 37 and ground surface 38. Transition section 10 is then coupled to transition section 9 by coupling means 16 which, in this instance, takes the form of a coaxial transmission line 40 to couple equal impedance points of transition sections 9 and 10 together.

The second transition section 10' of the output impedance matching device has substantially the same configuration as the transition section 10 of the input impedance device of Fig. 6 and also is disposed to have the longitudinal axis of cylinder 36' at right angles to the longitudinal axis of propagating structure 4. The coupling between transition sections 10' and 9' is accomplished in this instance as illustrated in Fig. 6 by transmission line 41 of a characteristic impedance equal substantially to the impedance of transition section 10' and transition section 9' at the point of coupling together. It is to be understood, however, that an extension of helical conductor 12' may also be used if warranted to accomplish the coupling between the two transition sections of the impedance matching device.

Hereinabove there has been discussed variations of an impedance matching device comprising two impedance transition sections cooperating together to provide the desired impedance match between a low impedance coaxial transmission line and a relatively high impedance helical propagating structure. It is to be remembered that in certain instances each of the transition sections may be employed separately to provide the desired impedance matching. However, in certain instances, the sections individually will not provide the desired impedance match and, therefore, must be used in the cooperative arrangement discussed hereinabove. It should be further pointed out that it is the spacing between the spiral conductor and the conducting ground surface in transition section 10' and the spacing between the conducting ground cylinder 11 and the helical conductor 12 which provides the change of impedance to enable the accomplishing of the impedance match between the relatively low impedance coaxial

transmission line and the relatively high impedance helical propagating structure of the traveling wave tube. That is, it is the height of a line conductor above a ground conductor which determines the impedance change in both of the transition sections. The impedance of the transition sections may be determined by the relationship

$$Z_0 = \frac{138}{\sqrt{\epsilon}} \log 10 \frac{4h}{d}$$

where h is equal to the spacing between the ground surface and the conductor, and d is equal to the diameter of the conductor and ϵ is equal to the dielectric constant of the dielectric material disposed between the conductor and the ground surface.

While I have described above the principles of my invention in connection with specific apparatus, it is to be clearly understood that this description is made only by way of example and not as a limitation to the scope of my invention as set forth in the objects thereof and in the accompanying claims.

I claim:

1. A broadband radio frequency impedance matching device for use between a wave energy propagating line having a relatively low characteristic impedance and a wave energy propagating line having a relatively high characteristic impedance comprising in combination first and second impedance transition sections, and means coupling equal impedance points of said first and second transition sections to each other, said first transition section including a first line-above-ground transmission line having a conducting cylinder and a helical conductor disposed within and coaxially of said cylinder, the spacing between said conducting cylinder and said helical conductor being tapered from a narrow spacing to a relatively wide spacing, and said second transition section including a second line-above-ground transmission line having first and second conductors, said second conductor having a substantially constant pitch spiral configuration, said first and second conductors being disposed in a tapered spaced relationship with respect to each other, said second transition section including a conductive disk disposed coaxially of and extending radially from a given axis and a conductive spiral disposed coaxially of said given axis and in tapered spaced relationship with respect to one of the planar surfaces of said disk to provide said second line-above-ground transmission line.

2. A device according to claim 1, wherein the spacing of said spiral and said planar surface is tapered from a wide spacing adjacent said given axis to a narrow spacing removed from said given axis.

3. A device according to claim 2, wherein said low impedance line is coupled to said second transition section at a point removed from said given axis having an impedance equal to its characteristic impedance and said coupling means is coupled to said second transition section at a point adjacent to said given axis having an impedance equal to the impedance of the narrow spacing of said first transition section.

4. A device according to claim 3, wherein said high impedance line is coupled to the point of wide spacing in said first transition section.

5. A broadband radio frequency impedance matching device for use between a wave energy propagating line having a relatively low characteristic impedance and a wave energy propagating line having a relatively high characteristic impedance comprising in combination first and second impedance transition sections, and means coupling equal impedance points of said first and second transition sections to each other, said first transition section including a first line-above-ground transmission line having a conducting cylinder and a helical conductor disposed within and coaxially of said cylinder, the

spacing between said conducting cylinder and said helical conductor being tapered from a narrow spacing to a relatively wide spacing, and said second transition section including a second line-above-ground transmission line having first and second conductors, said second conductor having a substantially constant pitch spiral configuration, said first and second conductors being disposed in a tapered spaced relationship with respect to each other, said second transition section including a conductive cylinder having its longitudinal axis parallel to the longitudinal axis of said high impedance line and a conductive spiral disposed coaxially of and extending along the longitudinal axis of said conductive cylinder in tapered spaced relationship with a surface of said conductive cylinder to provide said second line-above-ground transmission line.

6. A device according to claim 5, wherein said spiral is disposed within said conductive cylinder and in tapered spaced relationship with the inner surface of said conductive cylinder.

7. A device according to claim 6, wherein said low impedance line is coupled to said second transition section in the region of narrow spacing between said spiral and said conductive cylinder having an impedance equal to its characteristic impedance and said coupling means is coupled to said second transition section in the region of wide spacing between said spiral and said conductive cylinder having an impedance equal to the impedance of the narrow spacing of said first transition section.

8. A device according to claim 7, wherein said high impedance line is coupled to the point of wide spacing in said first transition section.

9. A broadband radio frequency impedance matching device for use between a relatively low impedance wave energy propagating line and a relatively high impedance wave energy propagating line comprising a transition section including a line-above-ground transmission line having a spiral conductor and a ground conductor, said spiral conductor having a substantially constant pitch, said spiral conductor and said ground conductor being disposed in a tapered spaced relationship with respect to each other, said high impedance line being coupled to said conductors in the region of the widest spacing thereof and said low impedance line being coupled to said conductors in the region of the narrowest spacing thereof, said transition section including a conductive disk disposed coaxially of and extending radially from a given axis and a conductive spiral disposed coaxially of said given axis and in tapered spaced relationship with respect to one of the planar surfaces of said disk to provide said line-above-ground transmission line.

10. A device according to claim 9, wherein the spacing of said spiral and said planar surface is tapered from a wide spacing adjacent said given axis to a narrow spacing removed from said given axis.

11. A broadband radio frequency impedance matching device for use between a relatively low impedance wave energy propagating line and a relatively high impedance wave energy propagating line comprising a transition section including a line-above-ground transmission line having a spiral conductor and a ground conductor, said spiral conductor having a substantially constant pitch, said spiral conductor and said ground conductor being disposed in a tapered spaced relationship with respect to each other, said high impedance line being coupled to said conductors in the region of the widest spacing thereof and said low impedance line being coupled to said conductors in the region of the narrowest spacing thereof, said transition section including a conductive cylinder having its longitudinal axis parallel to the longitudinal axis of said high impedance line and a conductive spiral disposed coaxially of and extending along the longitudinal axis of said conductive cylinder in tapered spaced relationship with a surface of said conductive

cylinder to provide said line-above-ground transmission line.

12. A device according to claim 11, wherein said spiral is disposed within said conductive cylinder and in tapered spaced relationship with the inner surface of said conductive cylinder.

13. In a traveling wave electron discharge device having a collector electrode, means to project an electron beam along a given path to said collector electrode, a helical wave energy propagating structure disposed in interacting relation with the electrons of said electron beam, and input and output coaxial transmission lines for said helical structure, an input and output broadband radio frequency impedance matching device for matching the characteristic impedance of said helical structure to the characteristic impedance of said input and output coaxial transmission lines, each of said impedance matching devices comprising a first transition section including a first line-above-ground transmission line having a conducting cylinder coaxially of the axis of said helical structure and a helical conductor disposed coextensive with, within and coaxially of said cylinder coupled to the appropriate end of said helical structure, the spacing between said conducting cylinder and said helical conductor being tapered from a relatively wide spacing adjacent the end of said helical structure to a relatively narrow spacing removed from the end of said helical conductor, a second transition section including a second line-above-ground transmission line having first and second conductors coupled to said coaxial transmission line, said second conductor having a substantially constant pitch spiral configuration, said first and second conductors being disposed in a tapered spaced relationship with respect to each other from a relatively narrow spacing adjacent said coaxial transmission line to a relatively wide spacing, and means coupling said second transition section in the wide spacing region thereof to said first transition section in the narrow spacing region thereof, said input and output coaxial transmission lines being disposed at opposite ends of said helical structure, said second transition section of each of said impedance matching devices including a conductive disk disposed coaxially of and extending radially from the axis of said helical structure adjacent the appropriate end thereof and a conductive spiral disposed coaxially of the axis of said helical structure and in tapered spaced relationship with respect to one of the planar surfaces of said disk to provide said second line-above-ground transmission line, the widest spacing between said spiral and said disk being disposed adjacent the axis of said helical structure and said coupling means includes an extension of said helical conductor.

14. In a traveling wave electron discharge device having a collector electrode, means to project an electron beam along a given path to said collector electrode, a helical wave energy propagating structure disposed in interacting relation with the electrons of said electron beam, and input and output coaxial transmission lines for said helical structure, an input and output broadband radio frequency impedance matching device for matching the characteristic impedance of said helical structure to the characteristic impedance of said input and output coaxial transmission lines, each of said impedance matching devices comprising a first transition section including a first line-above-ground transmission line having a conducting cylinder coaxially of the axis of said helical structure and a helical conductor disposed coextensive with, within and coaxially of said cylinder coupled to the appropriate end of said helical structure, the spacing between said conducting cylinder and said helical conductor being tapered from a relatively wide spacing adjacent the end of said helical structure to a relatively narrow spacing removed from the end of said helical conductor, a second transition section including a second line-above-ground transmission line having first and second conductors coupled to said coaxial transmission line, said second

conductor having a substantially constant pitch spiral configuration, said first and second conductors being disposed in a tapered spaced relationship with respect to each other from a relatively narrow spacing adjacent said coaxial transmission line to a relatively wide spacing, and means coupling said section transition section in the wide spacing region thereof to said first transition section in the narrow spacing region thereof, said input and output coaxial transmission lines being disposed at opposite ends of said helical structure, said second transition section of each of said impedance matching devices including a conductive cylinder having its longitudinal axis parallel to the axis of said helical structure disposed adjacent the appropriate end thereof and a conductive spiral disposed within, coaxially of and extending along the longitudinal axis of said conductive cylinder in tapered spaced relationship with the inner surface of said conductive cylinder to provide said second line-above-ground transmission line and said coupling means includes an extension of said helical conductor.

15. In a traveling wave electron discharge device having a collector electrode, means to project an electron beam along a given path to said collector electrode, a helical wave energy propagating structure disposed in interacting relation with the electrons of said electron beam, and input and output coaxial transmission lines for said helical structure, an input and output broadband radio frequency impedance matching device for matching the characteristic impedance of said helical structure to the characteristic impedance of said input and output coaxial transmission lines, each of said impedance matching devices comprising a first transition section including a first line-above-ground transmission line having a conducting cylinder coaxially of the axis of said helical structure and a helical conductor disposed coextensive with, within and coaxially of said cylinder coupled to the appropriate end of said helical structure, the spacing between said conducting cylinder and said helical conductor being tapered from a relatively wide spacing adjacent the end of said helical structure to a relatively narrow spacing removed from the end of said helical conductor, a second transition section including a second line-above-ground transmission line having first and second conductors coupled to said coaxial transmission line, said second conductor having a substantially constant pitch spiral configuration, said first and second conductors being disposed in a tapered spaced relationship with respect to each other from a relatively narrow spacing adjacent said coaxial transmission line to a relatively wide spacing, and means coupling said transition section in the wide spacing region thereof to said first transition section in the narrow spacing region thereof, said input and output coaxial transmission lines being both disposed adjacent the output end of said helical structure, said second transition section of said input impedance matching device including a conductive disk disposed coaxially of and extending radially from the axis of said helical structure adjacent the output end thereof and a first conductive spiral disposed coaxially of the axis of said helical structure and in tapered spaced relationship with respect to one of the planar surfaces of said disk to provide said second line-above-ground transmission line of said input impedance matching device, the widest spacing between said first spiral and said one planar surface being disposed adjacent the axis of said helical structure and said means coupling includes a coaxial transmission line extending to the input end of said propagating structure and said second transition section of said output impedance matching device including a second conductive spiral disposed coaxially of the axis of said helical structure and in tapered spaced relationship with respect to the other of the planar surfaces of said disk to provide said second line-above-ground transmission line of said output impedance matching device, the widest spacing between said second spiral and said other planar surface being disposed adjacent the

axis of said helical structure and said means coupling includes an extension of said helical conductor of said first transition section of said output impedance matching device.

16. In a traveling wave electron discharge device having a collector electrode, means to project an electron beam along a given path to said collector electrode, a helical wave energy propagating structure disposed in interacting relation with the electrons of said electron beam, and input and output coaxial transmission lines for said helical structure, an input and output broadband radio frequency impedance matching device for matching the characteristic impedance of said helical structure to the characteristic impedance of said input and output coaxial transmission lines, each of said impedance matching devices comprising a first transition section including a first line-above-ground transmission line having a conducting cylinder coaxially of the axis of said helical structure and a helical conductor disposed coextensive with, within and coaxially of said cylinder coupled to the appropriate end of said helical structure, the spacing between said conducting cylinder and said helical conductor being tapered from a relatively wide spacing adjacent the end of said helical structure to a relatively narrow spacing removed from the end of said helical conductor, a second transition section including a second line-above-ground transmission line having first and second conductors coupled to said coaxial transmission line, said second conductor having a substantially constant pitch spiral configuration, said first and second conductors being disposed in a tapered spaced relationship with respect to each other from a relatively narrow spacing adjacent said coaxial transmission line to a relatively wide spacing, and means coupling said second transition section in the wide spacing region thereof to said first transition section in the narrow spacing region thereof, said input and output coaxial transmission lines being both disposed adjacent the output end of said helical structure, said second transition section of said input and output impedance matching device each include a conductive cylinder having its longitudinal axis perpendicular to the axis of said helical structure disposed adjacent the output end thereof and a conductive spiral disposed within, coaxially of and extending along the longitudinal axis of said conductive cylinder in tapered spaced relationship with the inner surface of said conductive cylinder to provide said second line-above-ground transmission line and said coupling means includes a coaxial transmission line extending to said first section of the corresponding impedance matching device.

17. A broadband radio frequency impedance matching device for use between a wave energy propagating line having a relatively low characteristic impedance and a wave energy propagating line having a relatively high characteristic impedance comprising in combination first and second impedance transition sections, and means coupling equal impedance points of said first and second transition sections to each other, said first transition section including a first line-above-ground transmission line having a conducting cylinder and a helical conductor disposed within and coaxially of said cylinder, the spacing between said conducting cylinder and said helical conductor being tapered from a narrow spacing to a relatively wide spacing, and said second transition section including a second line-above-ground transmission line, a conductive disk disposed coaxially of and extending radially from a given axis and a conductive spiral disposed coaxially of said given axis and in tapered spaced relationship with respect to one of the planar surfaces of said disk.

18. A device according to claim 17, wherein the spacing of said spiral and said planar surface is tapered from a wide spacing adjacent said given axis to a narrow spacing removed from said given axis.

19. A device according to claim 18, wherein said low impedance line is coupled to said second transition section

at a point removed from said given axis having an impedance equal to the characteristic impedance of said low impedance line and said coupling means is coupled to said second transition section at a given point adjacent to said given axis having an impedance equal to the impedance of the narrow spacing of said first transition section.

20. A device according to claim 19, wherein said high impedance line is coupled to the point of wide spacing in said first transition section.

21. A broadband radio frequency impedance matching device for use between a relatively low impedance wave energy propagating line and a relatively high impedance wave energy propagating line comprising a transition section including a line-above-ground transmission line having a spiral conductor and a ground conductor disposed in tapered spaced relation, said high impedance line being coupled to said conductors in the region of the widest spacing thereof and said low impedance line being coupled to said conductors in the region of the narrowest spacing thereof, said transition section including a conductive disk disposed coaxially of and extending radially from a given axis and a conductive spiral disposed coaxially of said given axis and in tapered spaced relationship with respect to one of the planar surfaces of said disk to provide said line-above-ground transmission line.

22. A device according to claim 21, wherein the spacing of said spiral and said planar surface is tapered from a wide spacing adjacent said given axis to a narrow spacing removed from said given axis.

23. In a traveling wave electron discharge device having a collector electrode, means to project an electron beam along a given path to said collector electrode, a helical wave energy propagating structure disposed in interacting relation with the electrons of said electron beam, and input and output coaxial transmission lines for said helical structure, an input and output broadband radio frequency impedance matching device for matching the characteristic impedance of said helical structure to the characteristic impedance of said input and output coaxial transmission lines, each of said impedance matching devices comprising a first transition section including a first line-above-ground transmission line having a conducting cylinder coaxially of the axis of said helical structure and a helical conductor disposed coextensive with, within and coaxially of said cylinder coupled to the appropriate end of said helical structure, the spacing between said conducting cylinder and said helical conductor being tapered from a relatively wide spacing adjacent the end of said helical structure to a relatively narrow spacing removed from the end of said helical conductor, a second transition section including a second line-above-ground transmission line, first and second conductors coupled to said coaxial transmission line, the spacing between said first and second conductors being tapered from a relatively narrow spacing adjacent said coaxial transmission line to a relatively wide spacing, and means coupling said second transition section in the wide spacing region thereof to said first transition section in the narrow spacing region thereof, said input and output coaxial transmission lines being disposed at opposite ends of said helical structure, said second transition section of each of said impedance matching device including a conductive disk disposed coaxially of and extending radially from the axis of said helical structure adjacent the appropriate end thereof and a conductive spiral disposed coaxially of the axis of said helical structure and in tapered spaced relationship with respect to one of the planar surfaces of said disk to provide said second line-above-ground transmission line, the widest spacing between said spiral and said disk being disposed adjacent the axis of said helical structure and said coupling means includes an extension of said helical conductor.

24. In a traveling wave electron discharge device having a collector electrode, means to project an electron

beam along a given path to said collector electrode, a helical wave energy propagating structure disposed in interacting relation with the electrons of said electron beam, and input and output coaxial transmission lines for said helical structure, an input and output broadband radio frequency impedance matching device for matching the characteristic impedance of said helical structure to the characteristic impedance of said input and output coaxial transmission lines, each of said impedance matching devices comprising a first transition section including a first line-above-ground transmission line having a conducting cylinder coaxially of the axis of said helical structure and a helical conductor disposed coextensive with, within and coaxially of said cylinder coupled to the appropriate end of said helical structure, the spacing between said conducting cylinder and said helical conductor being tapered from a relatively wide spacing adjacent the end of said helical structure to a relatively narrow spacing removed from the end of said helical conductor, a second transition section including a second line-above-ground transmission line having first and second conductors coupled to said coaxial transmission line, the spacing between said first and second conductors being tapered from a relatively narrow spacing adjacent said coaxial transmission line to a relatively wide spacing, and means coupling said second transition section in the wide spacing region thereof to said first transition section in the narrow spacing region thereof, said input and output coaxial transmission lines being both disposed adjacent the output end of said helical structure, said second transition section of said input impedance matching device including a conductive disk disposed coaxially of and extending radially from the axis of said helical structure adjacent the output end thereof and a first conductive spiral disposed coaxially of the axis of said helical struc-

ture and in tapered spaced relationship with respect to one of the planar surfaces of said disk to provide said second line-above-ground transmission line for said input impedance matching device, the widest spacing between 5 said first spiral and said one planar surface being disposed adjacent the axis of said helical structure and said means coupling includes a coaxial transmission line extending to the input end of said propagating structure and said second transition section of said output impedance matching device including a second conductive spiral disposed coaxially of the axis of said helical structure and in tapered spaced relationship with respect to the other of the planar surfaces of said disk to provide 10 said second line-above-ground transmission line for said output impedance matching device, the widest spacing between said second spiral and said other planar surface being disposed adjacent the axis of said helical structure and said means coupling includes an extension of said helical conductor of said first transition section of said 15 output impedance matching device.
